US0D1025484S

(12) **United States Design Patent** (10) **Patent No.:** **US D1,025,484 S**
(45) **Date of Patent:** **** Apr. 30, 2024**

(54) **HAIR REMOVAL DEVICE**

(71) Applicant: **Church & Dwight Co., Inc.**, Princeton, NJ (US)

(72) Inventors: **David Stowers**, Morristown, NJ (US); **Eric Langberg**, Milford, PA (US)

(73) Assignee: **Church & Dwight Co., Inc.**, Princeton, NJ (US)

(**) Term: **15 Years**

(21) Appl. No.: **29/813,638**

(22) Filed: **Oct. 29, 2021**

(51) LOC (14) Cl. **28-03**

(52) U.S. Cl.

USPC **D28/45**

(58) **Field of Classification Search**

USPC **D28/44-46**

CPC **A45D 26/00; A45D 26/0061; B26B 21/00;**

Public Version, Slide from Retailer Presentation "Stray Hair Remover", p. 1, disclosed on Mar. 3, 2022, Church & Dwight Co., Inc.

Primary Examiner — Alison M Ofstun

(74) Attorney, Agent, or Firm — Womble Bond Dickinson (US) LLP

(57) **CLAIM**

The ornamental design for a hair removal device, as shown and described.

DESCRIPTION

FIG. 1 is a front perspective view of a hair removal device showing our new design;

FIG. 2 is a front view thereof;

FIG. 3 is a rear view;

FIG. 4 is a side view thereof;

FIG. 5 is another side view rotated 180 degrees relative to FIG. 4;

FIG. 6 is a top view thereof; and,

FIG. 7 is a bottom view thereof.

The broken lines shown in the drawings illustrate portions of the hair removal device and form no part of the claimed design.

1 Claim, 5 Drawing Sheets
